UNITED STATES PATENT OFFICE.

JOHN EDWIN KENKEL, OF GREAT FALLS, MONTANA.

HOLDER AND DELIVERY DEVICE.

1,121,509.

Specification of Letters Patent. Patented Dec. 15, 1914.

Application filed January 20, 1914. Serial No. 813,186.

To all whom it may concern:

Be it known that I, JOHN E. KENKEL, a citizen of the United States, and a resident of Great Falls, in the county of Cascade and State of Montana, have invented a new and Improved Holder and Delivery Device, of which the following is a full, clear, and exact description.

The invention relates to a device for delivering matches or toothpicks, and more particularly to a device in which the holder is mounted revolubly in a case and has a chamber or chambers to contain the articles to be delivered, and a means to locate individual articles from the mass, the idea being to deliver the articles singly or in small number, and in the case of toothpicks, an end being to avoid contaminating the mass of the picks and prevent contact of one's fingers with picks other than the pick or picks to be appropriated.

Objects of my invention are to provide a device of the indicated character, simple in construction and efficient in operation; to provide for accommodating a very large number of toothpicks or matches in a comparatively small space; to provide for the convenient manipulation of the device by successive users; and to provide a discharge or outlet adapted to be conveniently positioned for the delivery of the articles.

My invention resides in certain novel features relating principally to the construction and arrangement of a revolving container chamber or chambers, and a complementary radial extension thereof so formed as to retain and present individual toothpicks or matches; and it resides further in the manner of revolubly mounting the container chamber or chambers in a casing or support.

The invention will be particularly explained in the specific description following.

Reference is to be had to the accompanying drawings forming a part of this specification, in which similar characters of reference indicate corresponding parts in all the views.

Figure 1 is a side elevation of a holder and delivery device constructed in accordance with my invention; Fig. 2 is a transverse vertical section; Fig. 3 is a fragmentary detail in plan view of the revoluble structure, the view being given to indicate the adaptability of the device to hold an advertising card or the like; and Fig. 4 is a

fragmentary detail end view of a stop device employed in connection with the structure.

In constructing a device in accordance with the illustrated example, a casing 10 is provided, desirably having a flat bottom to rest on a table, counter, or other support, and presents a front side 10^a and a rear side 10^b, the latter being extended upwardly beyond the front side. Desirably the front side has an upper portion 10^c hinged as at 11, and provided with a fastener 12 pivoted as at 13, adjacent to the joint, to overlap the latter, and provided with a finger hold or lateral offset 14; the top of the casing is open.

In the case 10 is revolubly mounted a holder 15, by means of a spindle 16, in a manner hereinafter more particularly explained. The revoluble holder turns about the spindle 16 as an axis, and in addition to the hub portion thereof, a peripheral wall 17 is provided radially outward from the hub, and radially or approximately radial partitions 17^a, thereby providing a series of chambers 18, each adapted to receive a supply of toothpicks or matches, indicated by the letter A. The chambers are provided with extensions or pockets 19, disposed radially outward from the chambers, and communicating with the latter. There may be one or more chambers 18 and the complementary extensions 19. Each extension is desirably formed with an arched outer wall 20.

The side walls 21 of the throat establishing communication between the chamber 18 and its extension 19, are slightly convergent to contract the throat adjacent to the extension or pocket 19. The outer wall 20 of the pocket overhangs at each side beyond the side walls 21 of the throat, and is given a form to provide an elongated depression or retaining recess 23, adapted to hold one, or at least a very small number of toothpicks A. The extensions 19 and their retaining recesses 23 range transversely of the revoluble holder at intervals around the periphery of the latter. An extension 19 is of less length than the peripheral wall 17 of the holder, and said pocket or extension has an open end in the direction of the shorter side wall 10^a of the case, said open end being thus depressed within the adjacent end of 110 the holder proper and its peripheral wall 17. Moreover the extension 19 projects

radially outward beyond the wall 10^a when the holder is turned to bring a pocket to the open top of the case.

By the described construction, as the holder 15 is revolved, the matches or toothpicks A, when a chamber 18 is turned to the underside of the holder, will gravitate toward the now lowermost extension 19, and a quantity of the articles will be crowded through the throat into the said extension. As the holder is turned to bring the extension to the upper side, the articles will gradually drop from the extension and return to the chamber, but one or more of the toothpicks will be crowded laterally into the retaining depression or depressions 23, and be thus retained in the latter. By reason of the depressed open discharge end, a toothpick or match will lie in the extension with an end projecting, as clearly shown in Fig. 2, in position to be conveniently grasped and appropriated by the person manipulating the device. The contracted throat and the arched form of the outer peripheral wall 20 of the extension or pocket 19, contributes to the crowding of individual toothpicks or matches radially into the retaining depression, as will be readily understood.

The overhanging sides of the walls 20 at the juncture of the same with the throat walls 21 present exterior reentrant recesses, and opposed recesses are adapted to receive the ends of an advertising business card 24 between each two extensions 19, so that the cards will be firmly but detachably held in place, and different cards will be successively presented to view in the turning of the holder.

Referring more particularly to Figs. 2 and 4, the spindle 16 is rigidly held to a wall, as 10^b, of the case by forming a shoulder 25 near one end of the spindle, and providing a screw thread 26 outward from the shoulder, the threaded end being adapted to be passed through the end wall of the case and to receive a clamping nut 27. Inner and outer washers 28, 29, may be employed on the spindle to give a better binding action on the case.

The holder at the hub presents end disks 30, 31, on the spindle 16, these end disks having threaded engagement in the hub of the revolving holder so that the said holder will turn about the fixed spindle 16.

In order to provide a stop or brake to arrest the turning of the holder about the spindle, and locate a pocket or extension in proper position at the open top of the case, one end of the spindle is provided with a head 33, which is depressed within the end of the hub, being accommodated in an end chamber 32 in the said hub. The head 33 is formed with a peripheral series of depressions or notches 34, and a dog 35 is pivoted

on the adjacent disk 31, so as to turn relatively to the fixed head 33. A lug or stud 37 on the dog 35 is adapted to be pressed into an opposed recess by a retractile spring 38. Thus as the holder is turned by the operator taking hold of a wall 20 of the pocket, the dog 35 will turn about the head 33, the walls of the notches 34 serving to engage the lug 37 of the dog 35 and force it out of the notch; the action of the spring 38, however, is sufficient to prevent the accidental turning of the holder.

The hinged portion 10^c of the side wall 10^a affords access to the chambers 18 in succession, for charging the same with a supply of toothpicks or matches.

Having thus described my invention, I claim as new and desire to secure by Letters Patent:

1. A holder and delivery device of the character described, comprising a revoluble holder having a chamber, and a communicating extension radially outward from the chamber and having an end discharge.

2. A holder and delivery device of the character described, comprising a case, and a revoluble holder in the case having a chamber and an extension on the chamber communicating radially therewith, said extension having an open end constituting a discharge outlet.

3. A holder and delivery device of the character described, comprising a case having an open top, and a holder revolubly mounted between side walls of the case, said holder having a chamber provided with a peripheral wall, and an extension or pocket complementary to the chamber and disposed transversely of the holder, the extension being radially outward from the chamber and its periphery and adapted to project beyond one of the side walls of the case, said extension terminating at one end short of the adjacent end of the peripheral wall of the chamber and being open at said end, the outer peripheral wall of the pocket being fixed, and there being an elongated retaining depression for individual articles at a side of the pocket.

4. A holder and delivery device of the character described, comprising a revoluble structure comprising a containing chamber provided with a radial extension or pocket having an arched, outer peripheral wall, a throat leading from the chamber to the extension and having outwardly convergent walls, and elongated depressions in the extension at each side adjacent to the outer end of the throat.

5. A holder and delivery device of the character described, comprising a case having an open top and presenting side walls, one of which projects upwardly beyond the other, a revoluble structure mounted in the case, said structure having a container

chamber, and a radial extension complementary to the chamber, said extension having an open end constituting an outlet adjacent to the shorter wall of the casing, and the extension being adapted to be positioned to project upwardly beyond the said shorter wall.

6. A holder and delivery device of the character described, comprising a revoluble structure having a container chamber, a radial extension to said chamber, a throat establishing communication between the

chamber and extension, said extension presenting an outer peripheral wall overhanging exteriorly beyond the sides of the throat 15 and presenting reentrant recesses at the exterior.

In testimony whereof I have signed my name to this specification in the presence of two subscribing witnesses.

JOHN EDWIN KENKEL.
